ERNST G. EKSTROM, OF LOS ANGELES, CALIFORNIA.

ELECTROLYTIC PROCESS OF TREATING ALKALINE COMPOUNDS.

1,003,041.

Specification of Letters Patent. Patented Sept. 12, 1911.

Application filed December 7, 1910. Serial No. 596,012.

To all whom it may concern:

Be it known that I, ERNST G. EKSTROM, a citizen of Sweden, residing at Los Angeles, county of Los Angeles, State of California, have invented new and useful Improvements in Electrolytic Processes of Treating Alkaline Compounds, of which the following is a full, clear, and exact description.

This invention relates to a process for 10 the manufacturing of caustic soda. By the processes heretofore commonly employed for the purpose of manufacturing caustic soda chlorin gases are liberated in large quantities and partially allowed to escape into the 15 atmosphere, making it very dangerous and destructive to life and material, an economical loss in this way being inevitable.

The object of this invention is to provide a 20 process of manufacturing alkaline-hydroxids electrolytically from their salts without liberating any suffocating gases, but instead obtaining valuable acids as by-products.

In order to set forth the process I give as 25 an example my process applied in the manufacturing of sodium hydroxid by using sodium chlorid, as follows:

Method A.—First, the preparation of the 30 electrolyte: The sodium chlorid is dissolved in water to form a solution, which is treated in a wooden tub or similar vessel, with a predetermined quantity of hydrofluosilicic acid, H_2SiF_6 . In treating the salt with this acid a white sediment of sodium-fluosilicate, 35 Na_2SiF_6 , is precipitated, separating a solution of hydrochloric acid, HCl . The reaction which takes place is as follows:

40 The solution of hydrochloric acid is decanted from the precipitate and is collected in a special tank. The white sediment or precipitate remaining in the tub is washed with water in order to eliminate every possible trace of chlorin in the state of hydrochloric acid or sodium chlorid, (excess). To the sediment or precipitate, Na_2SiF_6 , an aqueous solution of hydrofluosilicic acid is added, bringing part of the sediment into 45 solution and forming an electrolyte.

Second, the electrolysis: Having produced 50 an electrolyte in the manner described above, I introduce a quantity of the same in a suitable vessel in which a porous diaphragm is inserted dividing the cell into two compartments, and in each of these compartments a

graphite-electrode is suspended on copper conducting strips. One of these electrodes forms an anode and the other one a cathode, when the electric current is sent through the 60 solution. In the electrolyte which is in the anode compartment, I introduce an excess of sodium fluosilicate, still undissolved and in this way I keep the electrolyte continually saturated with this salt. After having 65 acidified or alkalified the water of the cathode compartment, in order to increase its electric conductivity, the apparatus is ready for electrolysis. When the circuit is closed the electrolyte becomes decomposed 70 into its ions, sodium, Na_2 , being cation and fluosilicon, SiF_6 , being an ion, the two of which are migrating to the cathode and anode respectively. This decomposition is 75 the primary reaction which is a direct consequence of the electrolysis. As soon as these two ions are set free at the electrodes, a secondary reaction with the surrounding water will immediately take place, that is, in practice it occurs simultaneously with the liberation 80 of the two ions. In the cathode compartment, thus, the sodium-ion exerts chemical action upon the water forming sodium hydroxid, $NaOH$, that is caustic soda, liberating hydrogen, H , and in the anode compartment, the fluosilicon-ion SiF_6 , is converted 85 into hydrofluosilic acid, liberating oxygen, O . These two reactions take place in accordance with the following chemical equation:

90 In this way I produce caustic soda as a catholyte and bring about a regeneration of hydrofluosilicic acid from the anolyte enabling both of these substances to be drawn off separately, the alkali to be concentrated 100 and the acid to be used for making new electrolyte. If it is desired to facilitate the reactions just given above, compressed air may be injected in order to bring the liquid in good circulation during the process. 105 Steam injection is also favorable as the solubility of the sodium-fluosilicate will be considerably increased by the higher temperature caused by the steam.

Third, the concentration of the lye of 110 caustic soda: The caustic soda produced as indicated above, may then be concentrated

by evaporating in common vacuum-pans with or without the use of heat.

Method B.—First, the preparation of the electrolyte is the same as mentioned in connection with Method A.

Second, the electrolysis: Having produced an electrolyte in the manner previously described, I introduce a quantity of the same together with an excess of precipitate in a suitable vessel with or without a diaphragm using a metallic cathode, such as, mercury and a graphite or carbon anode. When the circuit is closed the electrolyte becomes decomposed as before, the sodium-ions forming an amalgam with the metallic mercury and the fluosilicon-ions regenerating hydrofluosilicic acid with the water present, liberating oxygen. The alloy of sodium and mercury is drawn off into a suitable vessel and subjected to water leaving metallic mercury (which is used over again) and forming sodium hydroxid and liberating hydrogen in accordance with the following equation:

25

Third, the concentration of the lye of caustic soda same as under Method A.

In the accompanying drawing, the figure shows in diagrammatic form a receptacle as 30 1 which is usually provided with a diaphragm 2 of porous material. Electrodes as 3 and 4 usually formed of graphite, are suspended by copper conducting strips 5 and 6 in the compartments formed upon each side 35 of the porous diaphragm. One of these electrodes acts as an anode and the other as a cathode. They are adapted to be connected in an electric circuit by any suitable wiring as indicated at 7, a battery or other source of 40 electricity as at 8 being included in said circuit. The simple mechanism thus described is that employed in carrying out Method A heretofore described. In carrying out Method B the porous diaphragm 45 may be used or may be taken out of the vessel as preferred. In carrying out Method B one of the graphite electrodes is replaced

by a metallic electrode as at the cathode, and the other electrode may be either graphite or carbon as at the anode.

The particular advantage of this process as compared with other methods using chlorin compounds for electrolysis, is that with my process no chlorin-gas is liberated as I do not use an electrolyte containing 55 chlorin as a constituent thus perfectly eliminating this trouble. Instead the chlorin will be found in the compound stated of hydrochloric acid which is a valuable by-product and can be used for commercial purposes as 60 well as for the manufacturing of calcium chlorid, magnesium chlorid, etc., and indirectly for the making of sodium carbonate.

What I claim is:—

1. The process of manufacturing alkaline 65 hydroxids and their derivatives, which consists in the electrolysis of an aqueous solution of a complex alkali-fluorin compound.

2. The process of manufacturing alkaline 70 hydroxids and their derivatives comprising the electrolysis of an aqueous solution of a complex alkali-fluorin compound between graphite electrodes and separating said electrodes by a diaphragm.

3. The process of manufacturing alkaline 75 hydroxids and their derivatives comprising the electrolysis of a solution of a complex alkali-fluorin compound, such as sodium fluosilicate, between a carbon anode and a metallic cathode.

4. The process of manufacturing alkaline 80 hydroxids and their derivatives consisting in the electrolysis of a solution of a complex alkali-fluorin compound such as sodium fluosilicate between a carbon anode and a metallic cathode such as mercury.

In witness that I claim the foregoing I have hereunto subscribed my name this 29th day of November, 1910.

ERNST G. EKSTROM.
